UNITED STATES PATENT OFFICE.

JOSEPH LUCIUS, OF SOLON SPRINGS, WISCONSIN.

PADDLE-LOCK.

1,368,341.

Specification of Letters Patent. Patented Feb. 15, 1921.

Application filed November 26, 1920. Serial No. 426,459.

To all whom it may concern:

Be it known that I, JOSEPH LUCIUS, a citizen of the United States, residing at Solon Springs, in the county of Douglas and State 5 of Wisconsin, have invented certain new and useful Improvements in Paddle-Locks, of which the following is a specification, reference being had therein to the accompanying drawing.

10 This invention relates to means for assisting in the paddling of a canoe and which may be properly referred to as a paddle lock, it performing to a large extent the same functions in connection with a paddle that 15 an oar lock does to an oar in a row boat.

The object of my invention is, in a sense, two fold; that is, one object being to prevent the wearing or abuse of a canoe and paddle incident to the use of the latter, and the 20 other object is, as before stated, to assist in the paddling and manipulating operations of the canoe.

Other objects and advantages of the peculiarities of the device will appear in the 25 further description thereof.

In the accompanying drawings forming part of this application and in which like reference characters indicate like parts:

Figure 1 is a plan view of one of my 30 proved paddle locks,

Fig. 2 is an edge elevation of Fig. 1,

Fig. 3 is a perspective view of a canoe equipped with one of my paddle locks showing its relation to a paddle in action, and

35 Fig. 4 is a transverse sectional view of the gunwale of a canoe with the paddle lock applied thereto.

The device comprises an elongated, narrow, wearing, base plate 1, which is designed 40 to be embedded within or securely attached to the gunwale 2 of the canoe and that at a point on the gunwale where the canoeist normally engages same with the stock of the paddle. Adjacent one end of the base plate 45 1 and centrally thereof is an inclined protrusion or lock 3, the inclination of the protrusion being outwardly asternwise and terminating at its after end abruptly, or preferably with a slight overhang as shown in 50 Fig. 2 so that in the event of the canoeist

wishing to use his paddle as a scull he may do so by placing it against the after end of the protrusion, as is obvious.

It is well known that many canoeists make an effort to keep their paddle stock away 55 from the gunwale of the canoe, but, nevertheless this requires very special effort and it is universally the practice to more or less slidably engage the gunwale with the stock of the paddle and especially is this true during 60 the stroke when the canoeist aims to influence the course of his canoe adversely to the normal forward stroke of the paddle; or, in other words, feathers his paddle while in the water to maintain a straightaway 65 course. At this time he would naturally bring his paddle to the point on the gunwale provided with the protrusion or paddle lock above described when the same will act as a fulcrum upon which to finish the stroke. 70 The inclination of the forward side of the protrusion is to prevent forming an abrupt stopping place for the paddle as this might prove objectionable to some canoeists and especially so to one not familiar with the 75 advantages of the lock.

It is evident that this lock and plate may be made of either metal or some more resilient material, such as vulcanized rubber, or the like.

Having thus described my invention what I claim and desire to secure by Letters Patent, is:

1. The combination with a canoe, of an outwardly extending forwardly and inwardly inclined projection upon the gunwale thereof adjacent the end of the canoe from which the latter is paddled.

2. The combination with a canoe, of a wearing plate having an outwardly extending forwardly and inwardly inclined projection thereupon, substantially as and for the purpose described.

3. The combination with a canoe having a gunwale thereupon, of an outwardly extending, forwardly and inwardly inclined, paddle lock upon the gunwale, substantially as described.

4. The combination with a canoe, of a paddle receiving lock projecting outwardly 100

upon the gunwale thereof adjacent the end of the canoe from which the latter is paddled.

5. The combination with a canoe, of an outwardly projecting paddle lock carried by the gunwale of the canoe adjacent the end from which the latter is paddled for frictional engagement with the stock of the

paddle while in motion to assist in steering the canoe.

In testimony whereof I hereunto affix my signature in the presence of two witnesses.

JOSEPH LUCIUS.
